UNITED STATES PATENT OFFICE.

FRANK B. MANLY, OF MALTA, OHIO.

PLOW.

SPECIFICATION forming part of Letters Patent No. 369,727, dated September 13, 1887.

Application filed September 16, 1886. Serial No. 213,661. (Model.)

To all whom it may concern:

Be it known that I, FRANK B. MANLY, a citizen of the United States, residing at Malta, in the county of Morgan and State of Ohio, 5 have invented certain new and useful Improvements in Plows, of which the following is a specification.

My invention relates to improvements in that class of plows known as "cultivators," in which two sets of shovels are carried by rearwardly-extending beams, each of the latter being so constructed and attached to the supporting-frame as to admit of its being given an independent vertical or lateral movement at the will of the operator; and the objects of my invention are, first, to so pivot an elongation of the beams to the supporting-frame as to produce a length of beam sufficient to facilitate the lateral swinging motion, and to so connect said elongated portion to the body of the beam as to produce a shorter beam and lessen the weight to facilitate the vertical motion; second, to so connect said beams as to admit of the swinging motion of the beams and 15 shovels and allow the frame to remain in the same relative position with the pole or tongue of the cultivator; third, to provide peculiar means for the lateral adjustment of the connecting-arch rods. These objects I accomplish 20 in the manner illustrated in the accompanying drawings, in which—

Figure 1 is an inner side view of one of the beams and the parts to which it is connected. Fig. 2 is an outside view showing the wheel-bearing broken away and the wheel removed. 25 Fig. 3 is a plan view of the beam shown in Fig. 1. Fig. 4 is a plan view of the arch-rods and evener. Fig. 5 is a rear view of one of the beam-extensions, supporting-frame, and arch-rods. Fig. 6 is a sectional view in detail of the arch-rod bearing. Fig. 7 is a perspective view of the supporting-frame with its connections broken away.

Similar letters refer to similar parts throughout the several views.

A represents the supporting-frame, having formed on its rear side a transverse hollow bearing-piece, a , made to project slightly outward. On the outer projecting end of this 30 bearing-piece is formed a short rearwardly-projecting arm, a' , within which is made to bear the short transverse wheel-axle b , having

the wheel b' mounted thereon in the usual manner. Made to project forwardly from the front side of the outer projecting end of bearing-piece a is a short lug, to which is secured a forwardly-projecting arm, a^2 , which, extending slightly beyond the front of the wheel b' , is provided with an eye or other suitable connection, a^3 , to which may be hooked a single-tree, c . Extending obliquely rearward from this eye is a second arm, a^4 , having its rear end secured to the outer side of the frame A.

Bolted or otherwise secured to the frame A, at the angle formed by the projection of the outer end of the bearing-piece a , is the lower end of an upwardly-extending vertical stay-arm, d , the purpose of which is to retain the evener g^4 at a proper height.

e represents a connecting-arch having its lower end pivoted to the hollow bearing-piece a , and thence extending upwardly above the top line of the wheels terminates in a short inward transverse bend, and rests loosely within a hollow transverse bearing-arm, e' , the two inner ends of which are connected by means of a connecting-strip, e^2 , to which they are secured.

Formed in the upper side of the hollow bearing-arm e' is an oblong hole, e^3 , through which 80 is made to project the upper thickened side of a collar, f , the latter fitting loosely around the arch-rod e , and having a vertical screw-hole in its upper side, through which is made to pass a set-screw, f' .

The rear diverging portions of the tongue g rest on and are secured to the top side of the bearing-arms e' , near their inner ends. Said rear portions of the tongue extend forwardly and obliquely inward, and are connected near 90 their meeting-point by means of a transverse block, g' , which is pivoted to and made to rest upon the central portion of the evener g^4 .

Pivoted to each of the outer ends of the evener is a rearwardly-extending arm or rod, 95 h , having a hook formed on its rear end adapted to engage loosely with a clevis, h' , secured to the upper end of the vertical arm d . Made to extend diagonally from the arm d to the rear portion of the lug a^3 is a brace, h^2 , to retain the stay-arm or post d substantially vertical, and made to extend from the frame A, to which it is secured, is a brace-rod, h^3 , having a hook formed on its upper end adapted

to engage loosely with a perforated lug made to project from the under side of the outer end of the arm h , to retain said arm substantially horizontal, but permit it to swing laterally.

Projecting from the inner side of the frame A, near its front end, is a vertical hollow bearing-piece, i , to carry the pivot-bolt on the extension of the plow-beam.

10 B represents a casting adapted to form a forward extension of the beam l , and is provided with two arms, $k' k^2$, extending forwardly one above the other, the lower arm, k^2 , extending in a line parallel with the ground, and the upper arm, k' , extending obliquely upward until near its outer end, when it is bent forwardly in a line parallel to the lower arm, k^2 , the end of the latter being made to rest against the under side of the bearing-piece i , and the end 15 of the former being made to rest on the top side of said bearing-piece, and be braced thereby. The arms are held loosely pivoted in this position by means of a pivot-bolt, k^3 , made to pass through the perforated ends of said arms, and 20 held by means of a suitable nut, k^4 .

25 The beam l , which is formed in the usual manner, of two rearwardly-extending connected arms, is loosely pivoted at its front end to the rear end of the extension-casting B by 30 means of a transverse pivot-bolt, k .

35 On the upper side of the arm k' is formed, near the middle of its length, a hook, k^5 , to which may be linked a spring holding-rod, n , so bent as to bring its two halves in a parallel 40 position, and made to extend horizontally through a spiral spring, n' , to the rear end of which is hooked the ends of said rod. Bolted to the inner side of one of the beam-arms l is an inwardly-projecting lug, m , carrying on 45 its projecting end a short vertical slotted arm, m' , its slotted surface being provided on one side with a number of notches to form a rack with which may be made to engage, at the desired height, the hooked end of a short arm, 50 o , the latter being pivoted at its remaining end to the rod o' , which, passing through the spring n' from its rear end, has its ends hooked to the front end of said spring.

55 p represents a pendent arm secured to the rear portion of the tongue, and having its lower end hooked to receive the beam when it is desired to suspend the latter above the ground.

The above description, although made with reference to one-half the cultivator for convenience, is also applicable to the remaining half.

By the construction above described it will be seen that, the beam l being pivoted to the rear end of the extension B, the former

may be given a vertical motion without carrying the weight of the extension with it, and that the spring n' tends to lighten the same. The pivot-bolt k^3 being located at a point in front of the axle, the length of beam is increased sufficiently to enable the operator in giving the shovels a lateral motion to avoid injuring plants, to cause the shovels to describe a greater arc of a circle, and thus keep the faces of the shovels more directly to the front. The spring n' , being secured to the beam and its extension only, retains its relative position with the beam while the latter is being swung to the right or left. It will also be seen that, the arch-rods e being held within the hollow arms e' by means of the set-screw f' , a lateral adjustment of said arch-rods may be obtained, when desired, to diminish or increase the distance between the parts, and that one of the beams may be advanced to a point beyond the other, the set-screw f' being made to pass through the collar f , instead of the bearing-arm e' , thus allowing the rod to turn in its bearings.

Having now fully described my invention, what I claim, and desire to secure by Letters Patent, is—

1. The combination, with the supporting frames A, of the beam-extensions B, pivoted vertically at their front ends near the front ends of said frames, shovel-beams l , pivoted transversely to the rear ends of said extensions, and spiral springs n' , having their holding-rod secured, respectively, to the beam-extension and to the beams, substantially as and for the purpose specified. 95

2. The combination of the frames A, having bearing parts $a' a' i$, and arms $a^2 a^4$, having eyes a^3 , with the pivoted beam-extensions B and beams l , arch-rods e , vertical stay-arms d , connecting with evener g^4 , arm h , and braces $h^2 h^3$, substantially as and for the purpose specified. 100

3. The combination of the frames A, having bearing parts $a' a' i$, and arms $a^2 a^4$, having eyes a^3 , with the pivoted beam-extensions B and beams l , arch-rods e , having hollow bearings e' , the latter having oblong openings e^3 , collars f and set-screws f' , and connecting-piece e^2 , substantially as and for the purpose specified. 105

4. The combination, with the cultivator arch-rods e and their bearing arms or sleeves e' , having openings e^3 , of the collar f , set-screws f' , and connecting-piece e^2 , substantially as and for the purpose specified. 110

FRANK B. MANLY.
